UNITED STATES PATENT OFFICE.

WILLIAM SMITH AND ANTON W. SMITH, OF LOS ANGELES, CALIFORNIA.

LAMP-HOLDER.

1,370,231.

Specification of Letters Patent.

Patented Mar. 1, 1921.

Application filed March 3, 1919. Serial No. 280,441.

To all whom it may concern:

Be it known that we, WILLIAM SMITH and ANTON W. SMITH, citizens of the United States, residing at Los Angeles, in the county of Los Angeles and State of California, have invented new and useful Improvements in Lamp-Holders, of which the following is a specification.

Our object is to provide a relatively simple, practical and readily adjustable electric lamp holder, and our invention consists of the novel features hereinafter shown, described and claimed.

Figure 1 is a side elevation showing a lamp holder embodying the principles of our invention supported on a wall.

Fig. 2 is a front end elevation looking in the direction indicated by the arrow 2 in Fig. 1, parts being broken away to show other parts.

Fig. 3 is a fragmentary top plan view as indicated by the arrow 3 in Fig. 1.

Fig. 4 is a fragmentary side elevation analogous to Fig. 1 and showing a modified form of a supporting bracket.

Fig. 5 is a top plan view as indicated by the arrow 5 in Fig. 4.

Fig. 6 is a view analogous to Figs. 1 and 4, and showing a portable stand support instead of the wall bracket shown in Fig. 1, or the post shown in Fig. 4.

Fig. 7 is a view analogous to Fig. 3 and showing a modified construction.

Referring to Figs. 1, 2 and 3, an attaching plate 1 is adapted to fit against the flat face of a wall 2 and be secured in place by screws 3 inserted through the plate into the wall. A vertical socket 4 extends inwardly from the attaching plate 1, thus producing a wall bracket 5. A lever 6 is mounted upon a pivot 7 in the socket 4 and in a slot 8, and the lower end of the lever 6 swings into the socket opening 9. The upper end of the lever serves as a handle, and a spring 10 is secured to the socket and engages the handle to throw the handle outwardly and the lower end inwardly to form a catch. The horizontal supporting arm 11 is formed integral with a vertical pintle 12, there being a shoulder 13 at the upper end of the pintle 12 to fit upon the upper end of the socket 4, and the pintle 12 fits rotatably in the opening 9. A recess 14 is formed in the pintle 12 to receive the catch formed by the lever 6, so that when the pintle is shoved

down into the socket the catch will hold the pintle from being withdrawn until the upper part of the lever is operated to compress the spring 10 and release the catch. A vertical bar 15 is rigid with the outer end 60 of the arm 11 and extends up and down. A fork 16 extends upwardly from the bar 15. The lazy tong lever 17 is hingedly connected to the upper end of the bar 15 by a pin 18. The second lazy tong lever 19 has its 65 lower end inserted through a vertical slot in the lower end of the bar 15, and pins 20 and 21 are fixed through the lower end upon opposite sides of the bar 15 so as to allow the bar to move up and down as required by the 70 lazy tong action. The levers 17 and 19 are connected by a pivot 22.

A plurality of lazy tong levers 23 are connected to the lower end of the lever 17 and to the upper end of the lever 19 by pivots 75 24 and 25. A vertical bar 26 is connected to the upper end of the last lazy tong lever 27 by a pivot 28, and the lower end of the last lazy tong lever 29 extends through a vertical slot in the lower end of the bar 26, 80 and pins 30 and 31 are inserted through the lever 29 on opposite sides of the bar 26 so as to allow the lever 29 to move up and down relative to the bar 26 as required by the lazy tong action. A fork 32 extends upwardly from the bar 26, and with fork 16 forms a convenient support for the lamp cord 33. A horizontal arm 34 extends forwardly from the center of the bar 26 and has a bearing 35, said bearing 35 having a 90 horizontal axis and the end faces of the bearing being corrugated, the spring arms 36 and 37 having bearings 38 and 39 fitting the corrugated faces upon the bearing 35. A bolt 40 is inserted through the bearings 39, 95 35 and 38, and a wing nut 41 is screw seated upon the bolt to clamp the bearings 38 and 39 against the bearing 35 to hold the spring arms 36 and 37 in an adjusted position. The outer ends 42 and 43 of the 100 spring arms 36 and 37 are curved outwardly and the central portions 44 and 45 of the spring arms are concavo-convex, so that the electric lamp socket 46 attached to the cord 33 may be passed between the ends 42 and 105 43 to the portions 44 and 45, and said portions 44 and 45 will embrace the neck of the lamp socket and hold it in position, as shown in Fig. 1. The spring arms 36 and 37 may be adjusted up and down by manip- 110

ulating the wing nut 41 to tilt the lamp 47 to any desired position. It is obvious that the lazy tong action will carry the lamp to and from the wall 2 to the limits of the action.

Referring to Figs. 4 and 5, the socket 48 is mounted in clips 49 and 50, and the clips 49 and 50 have split clamping bearings 51 and 52 adapted to engage a vertical post like a bed post 53, and the lazy tong construction shown in Fig. 1 may be removed from the wall bracket and inserted into the socket 48 when desired.

Referring to Fig. 6, the heavy stand base 54 has a socket 55 extending upwardly from its center, and the lazy tong construction shown in Fig. 1 may be removed from the wall bracket 5, or from the bed post bracket 56, shown in Fig. 4, and inserted into the socket 55.

Referring to Fig. 7, the lamp holding fork 57 has a screw threaded stem 58 removably screwed into a boss 59, and the boss 59 is carried by a bar similar to the bar 26, thus making a rigid connection between the lamp 60 and the lazy tong construction

instead of the adjustable joint shown in Fig. 3.

Various changes may be made without departing from the spirit of our invention 30 as claimed.

We claim:

A lamp holder comprising a vertically disposed socket, a spring catch arranged thereon, a pintle journaled in said socket and 35 provided with an annular notch that is adapted to receive the point of the spring catch, a vertically disposed bar connected to the upper portion of the pintle, a series of lazy tong levers pivotally connected to 40 said bar, a vertically disposed bar pivotally connected to the outer end of the lazy tongs, a lamp supporting bracket pivotally connected to the last mentioned bar and forks projecting upwardly from said vertically 45 disposed bar for supporting the current carrying wires that extend to the lamp that is positioned in said bracket.

In testimony whereof we have signed our names to this specification.

WM. SMITH.

ANTON W. SMITH
